UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR AN EYELET.

SPECIFICATION forming part of Design No. 25,835, dated July 28, 1896.

Application filed November 13, 1895. Serial No. 568,863. Term of patent 14 years.

To all whom it may concern:

Be it known that I, ELEAZER KEMPSHALL, of Newton, in the county of Middlesex and State of Massachusetts, have invented and produced a new and original Design for Eyelets, of which the following is a specification.

This invention relates to a new and original design for eyelets; and it consists in the novel features of shape and configuration herein-
after fully described and particularly claimed, and clearly illustrated in the drawing.

Reference is to be had to the accompanying drawing, forming a part of this application, in which like characters indicate like parts wherever they occur.

The figure represents a perspective view showing my design.

The essential feature of my design consists

in a tubular-shaped body, one of whose ends is formed with a series of projections, having 20 a laterally-extending part.

a represents a tubular-shaped body, one end of which is shown as formed with a series of projections *a'*, having laterally-extending parts or members *a''*. 25

I claim—

The design for an eyelet, substantially as shown and described.

In testimony whereof I have signed my name to this specification, in the presence of 30 two subscribing witnesses, this 7th day of November, A. D. 1895.

ELEAZER KEMPSHALL.

Witnesses:

A. D. HARRISON,
ROLLIN ABELL.
